TAX COMPUTER

Sarah Ann Ayres, Hermosa Beach, Calif.

Application January 23, 1951, Serial No. 13,926

Term of patent 14 years

(Cl. D52—2)

To all whom it may concern:

Be it known that I, Sarah Ann Ayres, a citizen of the United States and a resident of Hermosa Beach, in the county of Los Angeles, and State of California, have invented a new, original, and ornamental Design for a Tax Computer, of which the following is a specification, references being had to the accompanying drawing, forming a part thereof:

Figure 1 is a side elevational view of a tax computer showing my new design;

Figure 2 is a top plan view;

Figure 3 is another side elevational view; and
Figure 4 is an end view.

I claim:

The ornamental design for a tax computer, substantially as shown.

SARAH ANN AYRES.
